UNITED STATES PATENT OFFICE.

WILLIAM HUMPHREY KNOWLES AND WILLIAM FREDERICK GOREHAM, OF LONDON,
ENGLAND.

LUBRICATOR.

1,073,911.

Specification of Letters Patent. Patented Sept. 23, 1913.

Application filed September 19, 1912. Serial No. 721,266.

To all whom it may concern:

Be it known that we, WILLIAM HUMPHREY KNOWLES and WILLIAM FREDERICK GOREHAM, a citizen of the United States of 5 America and a subject of His Majesty the King of Great Britain, respectively, and both residents of London, England, have invented a certain new and useful Improvement in Lubricators, of which the following 10 is a specification.

This invention relates to improvements in lubricators of the class adapted to feed semifluid or thick lubricating material particularly graphite and oil, and which possess 15 a plunger or piston pump operated by a swash ring the position of which can be adjusted to obtain the desired stroke of plunger and consequently the amount of oil feed.

20 The object of the present invention is to improve the construction of lubricators of this class whereby they are rendered more certain in their action, in that vibration will not affect them and also are rendered 25 in an important respect proof against clogging.

As previously constructed the means for holding the swash ring in its operative position was liable to fail with vibration of the 30 lubricator so that the pump ceased to operate with the result that the heavy material such as graphite or hard pieces of other material would settle upon the face of the delivery valve and might prevent it from 35 closing.

The constructions of parts designed to avoid these difficulties is illustrated in the accompanying drawing to show one embodiment of the invention.

40 In this drawing:—Figure 1 is a sectional elevation of the lubricator according to the present invention. Fig. 2 is a part external elevation looking in the direction of the arrow Fig. 1. Fig. 3 is a front view of the 45 pointer shown in Fig. 2. Fig. 4 is a side elevation of the pointer, and Fig. 5 is a sectional elevation on an enlarged scale of the delivery valve shown in Fig. 1.

The lubricator comprises the usual casing 1 for the lubricant containing a pump barrel 2 carried in a housing 3 the latter being fixed in the casing while the barrel is revoluble by a worm 4, the shaft 5 of which is driven by any suitable means outside 55 of the casing and which worm engages

worm wheel 6 on the barrel. The wheel 6 drives through a pin 7 a stirrer 8 which prevents the heavy part of the lubricant from settling. The wheel 6 further carries a link 9 which enables it to rotate a lever 10 to 60 which it is connected at one end and which at the other end has a ball 11 carried between two cups 12, 12, forming a socket for the ball and which cups can slide in a channeled swash ring 13 pivoted on two oppositely arranged pins 14, 14 in the casing.

One end of the arm 10 is forked and pivots on two pins 15 (one being shown) of a spherical crosshead 15^a, through which passes the upper part of a plunger 16, which 70 is provided with fixing collars 17, 17, above and below the crosshead and tightening nuts, so that any rocking action of the lever 10 due to the angle at which the swash ring is set imparts a corresponding vertical reciprocation to the plunger 16 in the barrel 2. The plunger has a reduced diameter at 17 where it passes through a tubular piston 18 75 slidable in the barrel 2 and its end terminates in a cross head 19 and nut 20, the arrangement being such that the plunger has a slight additional movement over the piston 18 whereby an inlet opening at the point 21 is left on the upward stroke of the plunger and an outlet (which is permanent) 80 at 22 on the downward stroke of the plunger, the piston traveling with it in each case. The inlet for the lubricant to the plunger and piston is by way of the passage 23 in the stirrer. The pump barrel has screwed 85 to it a block 24 having a central passage (Fig. 5) and an annular hardened cutting edge 25 flared from within forming with the internally coned or outwardly flared and hardened surface of a block 26 a delivery 90 valve. The block 26 is pressed by a spring 27 to bring the cutting edge 25 and coned portion together. Screwed to the block 24 is a sleeve 28 to which in turn is screwed a tubular block 29 supporting the spring 27 100 such block 29 having outlet passages 30, 30 delivering into a screwed closing portion 31 of a sleeve 32 which is screwed in turn to and forms part of the casing 1. The block 29 carries a terminal rod 33 which enters the delivery pipe 34 and which carries a coil of wire 35 which is rotated with the rod 33 and stirs and propels the lubricant in the pipe 34 up to the point of use.

105 The swash ring 13 is tilted on its pivot 110

points 14 to alter its position and consequently the length of stroke of the plunger by means of a segment 36 (Fig. 2) and a pinion 37 preferably having teeth on a portion of the circumference only so that it can only be set to engage the segment correctly. Such pinion is carried by a spindle 38 squared at 39 which is supported in a sleeve 40 of the casing. The squared portion carries a pointer 41 Figs. 2, 3 and 4 the boss portion of which has a square opening 42 to fit the spindle, a slot 43 and groove 44 as shown in Figs. 1 and 4 so that a thumb nut or disk may engage with the pointer by means of a groove 43 and collar 46 which it carries. The pointer is able to slide to and fro on the squared portion of the spindle under the action of the thumb nut which is internally screwed and works on a reduced screwed portion 47 of the spindle. The pointer 41 is also adapted to engage a toothed segmental rack 48 screwed to or formed on the outside of the casing 1.

The pointer can only be disengaged from the rack by rotating the thumb nut on its screw which will result in drawing it, together with the pointer outwardly and away from engagement with the rack after which the spindle may be turned with the pinion 37 and segment 36 to tilt the ring 13 by moving the pointer to the right or left as desired, a return screwing movement of the thumb screw causing it to be forced inwardly and engage again with the rack at the point it is to be set, the screwing of the nut hard down upon the pointer finally locking it and the latter to the casing, so that the swash ring is fixed against any vibration of the lubricator. As the position of this swash ring varies, so does the stroke of the plunger 16 which at every downward movement of itself and piston 18 carries some of the lubricant with it the return movement allowing the lubricant to pass through opening 21 to the opening 22 down the passage of the block 24 to the outlet valve which under the pressure separates between the cutting edge 25 and coned seat in block 26 delivering the lubricant to the passage ways and pipe 34.

Should any hard substance or grit of the graphite or other hard material in the lubricant lodge in the delivery valve the hard knife like cutting edge cuts through it as it is forcibly pressed on to its hardened conical seat which takes place with a slight sliding action so that no obstruction of the valve can take place by substances lodging between the two members of same.

60 What we claim is:—

1. In a lubricator and in combination a container casing for the lubricant, a pump therein, a movable swash ring controlling the stroke of the pump, means for moving such swash ring, and means for setting same

in the desired position including a movable part, a rack with which such part can engage and means for withdrawing such part from the rack, and causing it to engage therewith after it has been moved, and the 70 position of the swash ring altered.

2. In a lubricator and in combination, a container casing for the lubricant, a pump therein, a movable swash ring controlling the stroke of the pump, means for moving 75 such swash ring comprising a segment carried thereby and a pinion, a rotatable spindle for the pinion, a pointer carried by the spindle outside the casing a rack with which such pointer engages, a thumb screw on the 80 spindle end, a collar on the thumb screw engaging a groove in the pointer and means for causing the pointer and spindle to move together, whereby rotation of the nut will withdraw the pointer from the rack, whereupon it may be turned to move the swash 85 ring and afterward reengaged with the rack and screwed fast to the casing.

3. In a lubricator and in combination, a container casing for the lubricant, a barrel 90 within the container, a slidable piston in the barrel, a plunger for the barrel, an inlet valve between the piston and plunger, a delivery valve, means for rotating the barrel, a lever connected to the plunger and barrel 95 rotating means, said lever being capable of rotation, a pivoted swash ring in which such lever rotates, means for rocking such swash ring and means for setting such swash ring in the desired position including a movable 100 part, a rack with which such part can engage and means for withdrawing said part from the rack after which it becomes rotatable and causing it to engage therewith after it has been rotated and the position of 105 the swash ring altered.

4. In a lubricator and in combination, a container casing for the lubricant, a pump therein, a movable swash ring controlling the stroke of the pump, means for moving 110 such swash ring, and means for setting same in the desired position including a movable part, a rack with which such part can engage, means for withdrawing such part from the rack, and causing it to engage 115 therewith after it has been moved, and the position of the swash ring altered, and a delivery valve for the pump comprising a hard seating and a hard cutting edge engaging therewith.

5. In a lubricator and in combination, a container casing for the lubricant, a pump barrel within the container, a slidable piston in the barrel, a plunger for the barrel, an inlet valve between the piston and plunger, means for rotating the barrel, a lever connected to the plunger and barrel rotating means, said lever being capable of rotation, a pivoted swash ring in which such lever rotates, means for rocking such swash ring 125 130

means for setting such swash ring in the desired position including a movable part, a rack with which such part can engage, means for withdrawing said part from the 5 rack after which it becomes rotatable and causing it to engage therewith after it has been rotated and the position of the swash ring altered, and a delivery valve for the pump comprising a hard cutting edge carried by a member of the valve and a hard seating carried by the other member one of

such members being attached to the barrel and the other being pressed to it by spring pressure.

In witness whereof we have hereunto set 15 our hands in the presence of the two subscribing witnesses.

WILLIAM HUMPHREY KNOWLES.

WILLIAM FREDERICK GOREHAM.
